UNITED STATES PATENT OFFICE.

EDGAR G. MORIN, JR., OF SAN FRANCISCO, CALIFORNIA.

COMBINATION GAUGE.

1,402,005.

Specification of Letters Patent. Patented Jan. 3, 1922.

Application filed September 16, 1920. Serial No. 410,600.

To all whom it may concern:

Be it known that I, EDGAR G. MORIN, Jr., a citizen of the United States, and resident of San Francisco, county of San Francisco, 5 State of California, have invented a new and useful Combination Gauge, of which the following is a specification.

The present invention relates to an improved gauge which is especially adapted 10 for use by carpenters joiners and like workmen in the marking of striking plate, lock, hinge mortise and other similar cuts on door jamb rabbets and similar structures.

The primary object of the invention is to 15 provide a simply constructed, compact, inexpensive, substantially constructed accurate and easily adjustable gauge which, after simply and easily effected adjustment, may be used for making various markings without necessitating readjustment for each different marking.

Another object of the invention is to provide a gauge of the character described which may be made of stamped bent or folded sheet 25 metal and will be small and light and may be conveniently carried in the pocket.

The invention possesses other advantages and features, some of which, with the foregoing, will be set forth at length in the following description wherein I shall outline in 30 full that form of the invention which I have selected for illustration in the drawings accompanying and forming a part of the present specification. In said drawings I have 35 shown one form of the construction of my invention but it is to be understood that I do not limit myself to such form, since the invention as expressed in the claims may be embodied in a plurality of forms.

Referring to the drawings Figure 1 is a 40 top plan view of the gauge showing it as it would appear when applied to a door and jamb, parts of which latter are shown in section; there being also shown a fragmentary plan of the gauge at one end as applied for 45 marking a hinge mortise. Figure 2 is a perspective view of the gauge showing it completely assembled, Figure 3 is a longitudinal 50 sectional view taken through the gauge, Figure 4 is a transverse sectional view of the gauge, Figure 5 is a perspective view of certain parts of the gauge shown in pre-assembled relation, Figure 6 is a perspective view 55 of a detail of the invention, Figure 7 is a perspective view of another detail of the in-

vention and Figure 8 is a perspective view of one of the adjustable plates.

The preferred embodiment of the gauge comprises rigidly joined rectilinear body plates (2) and (3) overlapped where joined 60 and spaced in parallel relation to one another for the most part. On the upper and lower sides of these plates are secured plates (4) and (5) having tongues (5^a) and shoulders (5^b) at their ends, the shoulders (5^b) being 65 flush with the outer ends of the body plates. The tongues extend into openings (5^c) formed in end plates (6) and (7) with the shoulders abutting said end plates. The end plates project outwardly equally at their 70 ends from the outer side of the plates (4) and (5) and also project outwardly an equal distance from the plates (2) and (3). These elements form a rectangular box-like body.

Similar longitudinally adjustable gauge 75 members (8) and (9) are mounted upon the plates (3) and (2) respectively with their outer ends projecting beyond the plates (6) and (7). At one end the member (9) is provided with an inverted U-shaped gauge member (11) having parallel gauge portions 80 (10) and (12) adapted to rest upon opposite faces of the door as shown at a and c of Figure 1, during the gauging and marking of the hinge mortise and other cuts. The member 85 (8) has an inturned right angular butt flange (13) on its outer end for engagement with the jamb rabbet shoulder as shown at b and the member (9) has a similar flange (14) for engagement with the jamb rabbet 90 shoulder at d. Screws (15) and (16) are inserted through longitudinal slots (25) and (26) in the members (8) and (9) and operate in threaded openings (16) in the plates (2) and (3) so as to adjustably hold the 95 members (8) and (9) in place. Screws (17) and (18) are inserted from the outside through the plate (4) for the purpose of actuating a clamping member which will be later described. A scribing point (19) is 100 formed on the edge of the plate (6) which edge projects beyond the plate (3) and this point is in line with the slot (26) in the member (8) and projects outwardly beyond said member (8). A similar scribing point 105 (20) is provided on the opposite edge of the plate (7) and this point is in line with the slot (25) and projects beyond the member (9). A scribing point (21) is provided on 110 the opposite edge of the plate (7) in the

same plane with the point (19) and projects through the slot (26).

The plate (3) has a right angular end (27) which has a scribing point (22) thereon which point projects through the plate (2) and through the slot (26) in the member (9). The point (22) is in line with and in the plane of the point (20), the member (11) being between these points.

10 The plate (2) is provided with a right angular flange (28) corresponding to the one (27) and spaced therefrom. The flange (28) abuts the plate (3) on its free end and has a projection (32) which is riveted in the plate (3) to lock the plates (2) and (3) firmly together.

Other scribing points (23) and (24) are provided on U-shaped gauge members (30) and (31) which are slidably mounted in the hollow space of the body between the plates (2), (3), (4) and (5) and the members (8) and (9). The U-shaped gauge members (30) and (31) are adjustably held in place by a clamping plate (29) against which the ends of the screws (17) and (18) abut. By screwing in these screws the plate (29) is forced to frictionally engage and clamp the members (30) and (31). The flanges (27) and (28) are notched on one edge as at (29') so as to accommodate said plate (29) and permit of a symmetrical body formation as shown particularly in Figure 5. The point (23) is formed on the end of the member (30) and projects through the slot (25) a distance equal to the projection of the point (22). The point (24) is formed on the opposite end of the member (31) and projects through the slot (26) as does the point (21). Opposite sides of the members (30) and (31) are engaged by the plates (29) and (5) and the ends of said members engage the members (8) and (9) whereby the said members (30) and (31) are snugly and accurately seated in the body 45 and accuracy of gauging and marking is provided. A scribing point (25) is provided on the free edge of the flange (18). This point is in line with the other points but in a plane between the plane of the other points and is for the purpose of marking the depth of the hinge leaf mortise along the face of the door as at E in Figure 1.

Operation.—To mark the cut for the lock at the front edge of the door parallel marks spaced apart equal to the width of the face of the locks are cut in said edge. This is gauged by loosening the screw (18) and moving the member (30) so as to bring the point (23) a distance from the fixed point (22) equal to the width of the lock. The screw (18) is then tightened and the clamp plate (29) is caused to frictionally engage and hold the member (30) and point (23) in adjusted position. These points (22) and (23) are next positioned or centered upon

the door so as to assume the position shown at a in Figure 1, by moving the member (9) so that the gauge surface (10) is the proper distance from the fixed point (22) whereby the points will be centered. The screw (15) is then tightened to hold the plate (9) in adjusted position. The operator now places the surface (10) against the edge of the door and moves the gauge up and down with the points (22) and (23) pressing upon the edge of the door so as to mark the width of the lock cut.

To gauge the points (21) and (24) for the striking plate marking on the jamb rabbet as shown at b in Figure 1, the member (31) is moved to bring the point (24) a distance from the fixed point (21) equal to the width of the striking plate and the set screw (17) is tightened so as to press the clamp plate (29) upon and hold the member (31) and point (24) in adjusted position. The member (8) is next moved so as to bring the butt-flange (13) into engagement with the shoulder of the jamb rabbet as at b in Figure 1, whereby the points (21) and (24) may be positioned to mark at the desired points on the jamb rabbet. The screw (17) is then tightened and the flange (13) is set in position. With the butt-flange (13) and points in the position by now moving the gauge vertically and applying inward pressure thereto the striking plate mortise will be marked on the jamb rabbet. With the gauge adjusted as described for marking the lock and the striking plate cuts it is possible to readily and easily mark a plurality of such cuts without necessitating any readjustment of the gauge.

To use the gauge for marking hinge mortises on the door at the point C in Figure 1 and the hinge mortise on the jamb rabbet at d in Figure 1, the member (9) may be adjusted to bring the butt-flange (14) the desired distance from the fixed point (19) although with the member (9) adjusted for marking the lock cut it is usually unnecessary to move or adjust the member (9) for this hinge mortise marking. With the gauge in proper adjustment the butt-flange (14) is engaged with the jamb rabbet shoulder at d and the point (19) is pressed inwardly while the gauge is moved up and down. This marks the inner line of the mortise for the hinge leaf on the rabbet at d. By placing the gauge surface (12) against the face of the door as at C and moving the gauge up and down with the point (20) bearing on the door the mark for the other hinge leaf mortise will be made. The butt-flange (14) and the gauge surface (12) are at the ends of the member (19) and will be approximately equidistantly spaced from the fixed points (19) and (20) regardless of the adjustment of the member (9) except that the outer face

of the butt (14) is spaced farther from the point (19) than the surface (12) is from the point (20), a distance equal to the thickness of the butt (14). Thus the mark is so cut 5 on the jamb rabbet at *d* that when the hinge leaf is placed in the mortise there will be a clearance between the face of the door and the jamb rabbet shoulder equal to thickness of the butt-flange (14). This allows for 10 warping, etc.

To mark the depth of the hinge leaf mortise the plate (8) is adjusted to bring the point (25) at a point spaced from the outer face of the end plate (7) a distance equal to 15 the thickness of the hinge leaf. The screw (16) is then tightened so that the parts will be held in this adjusted position. The outer side of the end plate (7) is then placed upon the edge of the door as shown at *E* in Figure 20 1 and the point (25) is engaged with the face of the door near the edge. The gauge is moved up and down the length of the hinge and the depth mark of the hinge leaf mortise will be scribed.

25 It will thus be seen that I have provided a marking gauge which may be put to different marking uses with little or no adjustment for each different use. Therefore with 30 my gauge it is possible to mark the lock, hinge and other mortise cuts on a plurality of doors, jambs, etc., more expeditiously, accurately, and with less work than is the case with the ordinary gauge.

I claim:

35 1. A gauge embodying in its construction a body structure, gauge members slidably mounted on opposite sides and projecting outwardly from the ends of the body, an inwardly turned butt-flange on the outer 40 end of each of said members, scribing points fixed on the ends of the body, spaced gauge portions on the inner end of one of said members and extending substantially at right angles to said member, adjustable scribing 45 points carried by the body between the fixed points on the body, a scribing point on the butt-flange of one of the gauge members, a scribing point fixed on the body between the ends thereof, and means for holding the 50 gauge members in adjusted position.

2. A gauge of the character described embodying in its construction a box-like body, members reciprocally mounted on the body, a clamp plate in the body, and arranged to 55 clamp upon said members, means for clamping portions of said plate upon said members, extensible gauge members having longitudinal slots therein, screws inserted through said slots and into opposite sides of the body 60 to hold the extensible members thereon, scribing points fixed on the body, and scribing points on the reciprocal members projecting through the slots and in a plane with the fixed points.

3. A gauge of the character described embodying in its construction a box-like body, members reciprocally mounted on the body, a clamp plate in the body, and arranged to clamp upon said members, means for clamping portions of said plate upon said members, extensible gauge members having longitudinal slots therein, screws inserted through said slots and into opposite sides of the body to hold the extensible members thereon, scribing points fixed on the body, 75 and scribing points on the reciprocal members projecting through the slots and in a plane with the fixed points, spaced parallel butt gauges on the inner end of one of the extensible members and butt flanges on 80 the outer ends of the extensible members.

4. A gauge of the character described embodying in its construction a box-like body, members reciprocally mounted on the body, a clamp plate in the body, and arranged to 85 clamp upon said members, means for clamping portions of said plate upon said members, extensible gauge members having longitudinal slots therein, screws inserted through said slots and into opposite sides 90 of the body to hold the extensible members thereon, scribing points fixed on the body, and scribing points on the reciprocal members projecting through the slots and in a plane with the fixed points, spaced parallel 95 butt gauges on the inner end of one of the extensible members and butt flanges on the outer ends of the extensible members and a scribing point on one of the butt flanges.

5. A gauge embodying in its construction 100 rectangular overlapped body plates having inturned right angular end flanges engaging the plates and spacing them in parallel relation to one another, top and bottom plates mounted upon opposite sides of the body 105 plates and having tongues at the ends thereof, end plates having openings receiving said tongues, a scribing point on one of said inturned ends and projecting through the opposite body plate, scribing points on the 110 end plates in the same plane with the first-named point, extensible gauge members mounted on the other opposite side of the body plate and having longitudinal slots therein, screws inserted through the slots 115 and into the body plate inturned butt flange on the outer ends of the extensible members, a double faced gauge member on the inner end of one of said extensible members, members reciprocal between the body plates, top 120 and bottom plates and extensible members, scribing points on said reciprocal members extending through said slots and in a plane with the other scribing point and means for holding the reciprocal members in adjusted 125 position.

EDGAR G. MORIN, JR.
